United States Patent Office

Des. 185,692
Patented July 21, 1959

185,692

GAMEBOARD

Jenell R. Anderson, Sunland, and Lee J. Dionne,
San Fernando, Calif.

Application August 11, 1958, Serial No. 52,160

Term of patent 3½ years

(Cl. D34—5)

Fig. 1 is a top plan view of the gameboard showing our new design.

Fig. 2 is an edge view as seen from the right of Fig. 1.

Fig. 3 is an enlarged fragmentary cross-sectional view as taken on the line 3—3 of Fig. 1.

We claim:

The ornamental design for a gameboard, substantially as shown.
